CLAIM

The ornamental design for a light-emitting diode (LED) floodlight, as shown and described.

DESCRIPTION

FIG. 1 is a front perspective view of a light-emitting diode (LED) floodlight showing our design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded front elevational view thereof.

The broken-line disclosure in the views is understood to represent portions of the light which form no part of the claimed design.

1 Claim, 7 Drawing Sheets
